UNITED STATES PATENT OFFICE.

GEORGE M. COCKE AND EMIL SEIDEL, OF MILWAUKEE, WISCONSIN, ASSIGNEES TO THE FULLER-WARREN COMPANY, OF SAME PLACE.

DESIGN FOR A STOVE.

SPECIFICATION forming part of Design No. 33,262, dated September 25, 1900.

Application filed August 27, 1900. Serial No. 28,258. Term of patent 7 years.

To all whom it may concern:

Be it known that we, GEORGE M. COCKE and EMIL SEIDEL, citizens of the United States, residing at Milwaukee, in the county of Milwaukee and State of Wisconsin, have invented and produced a new and original Design for Stoves, of which the following is a specification, reference being had to the accompanying drawing, forming a part thereof.

10 As shown in the drawing, which is a perspective view of a stove showing our new design, the leading or material features of the design consist of a top section *a*, of semi-spherical or dome shape, terminating in a plain circular rim which curves outwardly and downwardly and overhangs the body of the stove; a body-section *b*, of substantially cylindrical form, having in front a door-frame *c* and a feed-door *d*, extending approximately 15 from the bottom to the top of said body-section; a tapering fire-pot section *e*, contracted toward the bottom; an outwardly-projecting and downwardly-curved ledge or skirting *f*, overhanging the top of the fire-pot section *e*; 20 a base-section *g*, curving outwardly and downwardly from the bottom of the fire-pot section into an approximately-square form in horizontal section and having an ash-pit door *h* in the front side, and a skirting *i*, curving 25 outwardly and downwardly from the base-

section *g* and merging into legs *j*. The door-frame *c* has on each side margin a series of scroll or shell like ornaments in low relief, and between each side margin and the door *d* a band of scroll and leaf like ornaments. 35 Across the bottom of the door-frame is a row of rounded leaf-like or boss-shaped figures. The door *d* has a central ornamental shield *k*, which is surrounded by scroll and leaf like ornaments, and in the upper part of the door 40 is a circular damper *l*. The skirting *f* below the body-section *b* has scroll and leaf like surface ornamentation and leaf or shell like projections *m*, which join and overhang a plain circular foot-rail *n*. The base-section *g* 45 and the skirting *i*, together with the ash-pit door *h* and the legs *j*, have scroll and leaf like surface ornamentation.

Having described our invention, what we claim as new, and desire to secure by Letters 50 Patent, is—

The design for a stove as herein shown and described.

In witness whereof we hereto affix our signatures in presence of two witnesses.

GEORGE M. COCKE.
EMIL SEIDEL.
